UNITED STATES PATENT OFFICE.

CHARLES J. W. HAYES, OF ROCHESTER, MICHIGAN.

MECHANICAL FIGURE TOY.

1,110,685.

Specification of Letters Patent. Patented Sept. 15, 1914.

Application filed October 16, 1913. Serial No. 795,501.

To all whom it may concern:

Be it known that I, CHARLES J. W. HAYES, a citizen of the United States, residing at Rochester, in the county of Oakland and State of Michigan, have invented certain new and useful Improvements in Mechanical Figure Toys, of which the following is a specification, reference being had therein to the accompanying drawings.

This invention relates to mechanical figure toys and has for its object improved mechanism whereby animate movements are simulated and amusing postures executed by very simple and inexpensive means practical to employ with different kinds and sizes of figures, the very small as well as the larger sizes.

In the accompanying drawing: Figure 1 is a side view of my invention applied to the figure of a dog and shows a hand in position for operating it. Fig. 2 is a view of the toy shown in Fig. 1 as it appears after the actuating wire has been rotated one fourth of a revolution in one direction from the position shown in Fig. 1. The operator's hand, the manipulating piece and the fine wire connection are omitted from this and the succeeding views. Fig. 3 is a view of the toy shown in Fig. 1 as it appears after the actuating wire has been rotated one half of a revolution in either direction from the position shown in Fig. 1. Fig. 4 is a view of the toy shown in Fig. 1 as it appears after the actuating wire has been rotated three fourths of a revolution in one direction, or one fourth of a revolution in the other direction from the position shown in Fig. 1. Fig. 5 is a view from the front of the toy in the position shown in Fig. 1.

The figure portion of this toy comprises a fore part A, a middle part B and a hind part C.

The fore part A is provided with a head and supporting members and has a small round hole through it from front to back, this hole being central with a hemispherical joint-protuberance a^1 at the back.

The middle part B is a short length of cylindrical thin-wall tubing of a diameter commensurate with the fore and hind parts.

The hind part C is provided with supporting members, a hemispherical joint protuberance c^1 similar to that of fore part A and in the particular illustration herein shown, with a stub tail. There is also in the hind part C a small round hole passing

from front to back centrally through the joint protuberance.

The parts A, B and C are arranged in series on the actuating wire D which is journaled in the holes in A and C and passes freely through the hollow space of B. The hemispherical protuberances of A and C fit into the open ends of B forming universal "ball and socket" joints; and these parts thus jointed are held together by an eye at the front and a flattening "pinch" at the back in the ends of the wire D, which wire becomes the actuating element for the figure parts by virtue of a slight bend d^1 given it at about midway of its length between the joints. The wire D is connected at its eye end d^2 with a fine flexible transmission wire E the other end of which is fastened in the eye f of a larger manipulating wire F adapted to be rolled between the thumb and finger to rotate or oscillate the actuating wire D.

The toy should rest upon a display surface or medium on which it does not roll, but may freely slide on its supporting points, which are preferably made wide apart, whatever form they may take in the different figures to which this invention may be applied.

In operating this toy the manipulator is rolled between the thumb and finger and, preferably, at the same time, used to pull the toy along the table, the floor, the palm of the hand or whatever may be chosen for a display surface. The rotary component of the motion thus produced transmitted by the flexible wire to the crooked wire journaled in the figure parts, standing stable against overturning on the display surface, is there converted by the compelled conformity of these parts to the changing direction of crookedness of the wire as it rotates in them, into diverse motions of the parts which resemble more or less closely, movements of a living thing; and especially so when viewed in conjunction with the forward movement of the figure as a whole.

This invention may be applied to figures as different as those of dog and alligator or even man on hands and knees and the details of construction may be varied to a considerable extent without departing from the spirit of this invention which it is hereby purposed to protect.

What I claim is:

1. A mechanical figure toy comprising,

a fore part, a hind part and a wire journaled in and bent between the said fore and hind parts and extending through one of the said parts to a source of motion, substantially as specified.

2. In a mechanical figure toy, the combination of a fore part having supporting members, a hind part having supporting members, a middle part jointed with the said fore and hind parts and an actuating means comprising a plurality of journals connected together in angular relation.

3. A mechanical figure toy comprising, a plurality of figure parts adapted to rest upon and slide but not roll on a display surface, a crooked actuating member upon which the said figure parts are disposed in diversity of angular operative relation and means operatively connecting the said actuating member with a source of motion, substantially as specified.

4. In a mechanical figure toy, the combination of an actuating wire having a portion of its length at an angle to its axis of rotation and a figure-part journaled on said portion and adapted to bear upon a display surface whereby it is constrained to execute peculiar movements when said actuating wire is turned, substantially as specified.

5. In a mechanical figure toy, the combination of a plurality of figure-parts, a rotative actuating element engaging a plurality of said figure-parts, a manipulator adapted to be rolled between the thumb and finger, and a flexible rotative transmission

element connecting said manipulator and said actuating element whereby rotative motion is transmitted to said actuating element, substantially as specified. 40

6. A mechanical figure toy, comprising, a plurally limbed figure-part, the extremities of said limbs being relatively wide apart and adapted to slide and to laterally support said figure-part, a body figure-part, 45 and a crooked, rotative actuating element engaging said limbed figure-part between said wide-apart limb extremities less than enough above them to allow the torque from said actuating element in operation to overturn said figure-parts.

7. In a mechanical figure toy, the combination of a crooked, rotative actuating element, a body figure-part, and another figure-part provided with means preventing 55 the same being overturned laterally from operating engagement with said actuating element; said figure-parts being disposed on said actuating element in jointed operative relation.

8. In a mechanical figure toy, the combination of a unit part having head, shoulders and supporting members, a unit extremity part, means connecting the said parts in jointed relation and rotary actuating means, substantially as specified. 60

In testimony whereof I affix my signature in presence of two witnesses.

CHARLES J. W. HAYES.
